(57) CLAIM

The ornamental design for a “clock having gemstone cabochon hour position marks”, as shown and described.

DESCRIPTION

FIG. 1 is a perspective view of the top, front and right side of the clock;

FIG. 2 is a front elevation view of the clock;

FIG. 3 is a right side elevation view of the clock;

FIG. 4 is a top plan view of the clock;

FIG. 5 is a left side elevation view of the clock;

FIG. 6 is a view looking upwardly at the clock from below; and,

FIG. 7 is a perspective view of a second embodiment of FIG. 1, the only difference being that the array of marking stones forms a substantially circular pattern, rather than square pattern.

The broken-lines of FIGS. 1 through 7 depict a substantially planar clock face substrate, and a clock works comprising hour and minute hands. These broken line features are depicted for illustrative purposes only, and form no part of the claimed design.
